UNITED STATES PATENT OFFICE.

FREDERICK OTT, OF WOONSOCKET, RHODE ISLAND.

REED FOR LOOMS.

SPECIFICATION forming part of Letters Patent No. 717,905, dated January 6, 1903.

Application filed August 20, 1902. Serial No. 120,275. (No model.)

To all whom it may concern:

Be it known that I, FREDERICK OTT, a citizen of the United States, residing at No. 17 Maple street, Woonsocket, in the county of 5 Providence and State of Rhode Island, have invented certain new and useful Improvements in Reeds for Looms, of which the following is a specification, reference being had to the accompanying drawings.

10 My improvement relates to a reed designed more particularly for the weaving of fabrics of fine texture; and it consists in arranging the dents in a double row in staggered relation to each other, the dents of the rear row being provided with projections or bosses 15 along the line where the lathe beats up against the filling. In this way, without lessening the capacity of the reed to beat the filling evenly, I am able to very much decrease the 20 amount of friction to which the warp-threads are subjected by the action of the reed.

In the accompanying drawings, Figure 1 is a vertical longitudinal section of a reed containing my improvements, taken along the 25 line 1 1, Fig. 3. Fig. 2 shows one of the front set of dents. Fig. 3 is a vertical cross-section of the reed, showing the relation of the two sets of dents to each other. Fig. 4 shows one of the rear set of dents.

30 A 'A' are the bars of the reed-frame. 'a' is one of the front set of dents, its rear side being cut away, as shown in Fig. 2. 'b' is one of the rear set of dents, in which the front edge is similarly cut away. It is furnished at the proper point with a projection or boss 'c'. This projection is preferably rounded, as shown in the drawings. The two kinds of dents are inserted into the reed-frame alternately. The cut-away portions are deep 35 enough to create a clearance-space between the rows formed by the two sets of dents, except along the line where the two projections 'c' of the rear set are situated. These projections reach at their apex to the plane of the 40 front edges of the front set of dents.

45 Referring now to Fig. 3, it will be observed that as the lathe moves back and forth the threads during the greater part of the play of the reed are subjected to very little friction, because of the fact that the shed causes

the threads to pass between the dents where the cut-away parts create a free clearance-space—that is, where the side of the one dent and the proximate side of the adjacent dents are not alongside of each other. As the lathe 55 beats up against the filling the warp-threads as they approach each other occupy a position coincident to the row of bosses 'c'. The bosses cause the rear set of dents to perform their function of driving the filling home with 60 as great evenness and accuracy as though all of the dents were in exact alinement, as in the ordinary form of reed.

The usefulness of my invention will be especially apparent when consideration is given 65 to the amount of friction to which a knot or other enlargement in one of the warp-threads is necessarily subjected as the warps pass from the heddles to the take-up roller. Before the knot is out of reach of the friction of 70 the reed and woven into the fabric it must have passed back and forth along the sides of the dents, between which it is threaded many hundreds of times, depending, of course, upon the fineness of the texture of the fabric 75 which is being woven. In a fine reed this causes a large amount of friction, fraying out the thread and often breaking it. By staggering the reeds, as shown in my invention, this friction is greatly diminished or done 80 away with, and yet the presence of the bosses 'c' upon the rear set of dents enables me to obtain this advantageous result without sacrificing in any way the efficiency of the reed.

I am aware that a reed-frame having the 85 dents in staggered relation to each other is not in itself new, and I therefore make no claim to this construction by itself.

What I claim as my invention is—

1. A reed-frame having the dents arranged 90 in two sets in staggered relation to each other, the dents of the rear set having forwardly-projecting bosses, substantially as described.

2. A reed-frame having the dents arranged 95 in two sets in staggered relation to each other, the dents of the rear set having bosses which project forward to the plane of the front edges of the front set of dents, substantially as described.

3. A reed-frame having the dents arranged 100

in two sets in staggered relation to each other, the dents of the rear set having rounded bosses projecting forward to the plane of the front edges of the front set of dents, substantially as described.

4. A reed in which the dents are alternately cut away on the front and rear sides so that the working portions thereof are in staggered relation to each other with a clearance-space between; and bosses formed upon the front side of the rearmost dents coincident with the

plane at which the reed beats up against the filling, substantially as described.

In witness whereof I, FREDERICK OTT, have hereunto signed my name, with two subscribing witnesses, this 16th day of August, A. D. 1902.

FREDERICK OTT.
